HEAD LEVELLING AND HOLDING DEVICE

Lloyd L. Smith, Burwell, Nebr.

Application January 21, 1958, Serial No. 710,317

1 Claim. (Cl. 132—45)

This invention relates to a simple, practical and an effectual structural device which lends itself to advantageous use in a barber shop in that it functions to serve both the customer and the barber and keeps the customer's head level while getting a flat-top haircut.

It is a matter of common knowledge that present day barber shop practices call for the use of a recently patented level-equipped flat-top comb. The present head levelling and holding device is expressly, but not necessarily, adapted to be used in conjunction with the stated comb, the latter being used on the hair itself.

Briefly summarized, the concept has to do with a head levelling and holding device comprising a pair of companion arms adapted to occupy positions to the left and right, respectively, of the user's head, a level carried by one of said arms, and means for harnessing said arms on the person of the user and maintaining the arms in substantially perpendicular positions.

Novelty is predicated on the construction stated wherein the one arm mentioned is stationary while the other arm is adjustable in a vertical plane on a horizontal axis toward and from said one arm.

Construed from another point of view the invention pertains to a harness which is adapted to be temporarily applied to and worn by the user, a spirit level, and means operatively supporting the spirit level in a given position relative to the user's head, the harness preferably comprising a generally U-shaped neck embracing yoke which is adapted to rest upon the user's shoulders. In addition the structure includes stabilizing and retaining legs which are attached to and depend from each of the limbs of the yoke, the legs assuming approximately parallel relationship when in use and being adapted to rest upon the chest of the wearer.

More explicitly, the invention is directed to a U-shaped yoke embodying an adjustable bight portion and spaced parallel limbs, a first vertical arm integral with and perpendicular to the forward end portion of one limb and carrying level indicating means, a second arm cooperating with the first arm and hingedly connected to the forward end portion of the other limb, and legs attached to and depending from said limbs and adapted to rest upon the chest of the wearer.

Other objects, features and advantages will become more readily apparent from the following description and the accompanying drawing.

In the drawing, wherein like numerals are employed to designate like parts throughout the views:

Fig. 1 is a perspective view showing a user seated in a barber's chair and illustrating the head levelling and holding device constructed in accordance with the invention and in use;

Fig. 2 is a front elevational view of the same;

Fig. 3 is a plan view of the device by itself;

Fig. 4 is an exaggerated fragmentary elevational view detailing a hinge construction; and

Fig. 5 is a similar view also showing a hinge construction which is embodied to render the yoke adjustable.

With reference first to the yoke this is U-shaped in plan and is denoted, as an entity, by the numeral 6. It is of sectional construction and may be expanded to adapt itself to customers of varying size and stature. The bight portion embodies companion arcuate sections adjacent end portions 8 (Fig. 5) of which are flattened at 10 and

2

overlap to accommodate a bolt 12 held in place by a nut 14. There is a coil spring 16 surrounding the shank of the bolt assembled and held by the nut, and said spring has oppositely extending fingers 18 which press against the rearward surfaces of the sections 8 in a manner to press the limbs 20 of the yoke together, that is, when the bolt is loosened. The left hand limb has an upturned terminal portion 22 which, as seen in Fig. 4, has a flat upper end 24 pressed against a similar flat lower end 26 on the lower end portion of one of the gauging and positioning arms 28. Here again a bolt 30 is employed and this extends through overlapped ends, carrying a nut 32 and a coil spring 34 with its end portions 36 pressing against the components 22 and 28 respectively. The spring when the bolt is slightly loosened, tends to keep the arm 28 yieldingly and accommodately against the left cheek of the user's or wearer's head. The other limb 20 of the yoke is directed upwardly at 38 and joins with the relatively stationary arm 40. This is opposite to the arm 28 and extends along the right cheek in the manner illustrated. Its purpose is to serve not only as a brace for the wearer's head and face but also as a support for the spirit level 42. This, as shown in Fig. 2, embodies a suitable aluminum or lightweight block 44 equipped with a conventional bubble-type level 46. Thus, there is an adjustable horizontally disposable yoke carrying upstanding arms 28 and 40 equipped with appropriate level means. The yoke is a component of the over-all harness and the harness also includes a pair of retaining and stabilizing legs and these are seen best in Fig. 2 and are denoted by the numeral 48. The legs extend down over the chest of the wearer and have forwardly flared lower end or terminal portions 50. These legs in conjunction with the yoke provide highly adaptable and satisfactory harness, said harness supporting the two upstanding arms which, in turn, cooperate in presenting for the barber's use facilities desired in assisting him in giving the customer a flat-top haircut. The experimental model has been constructed out of components of aluminum tubing and the block carrying the level is also of lightweight aluminum. Perhaps commercial plastics of appropriate grade will do just as long as the over-all device is light in weight, easy to keep clean, easy to handle and package and otherwise convenient when serving the barber and the customer.

The foregoing is considered as illustrative only of the principles of the invention. Further, since numerous modifications and changes will readily occur to those skilled in the art, it is not desired to limit the invention to the exact construction and operation shown and described, and accordingly, all suitable modifications and equivalents may be resorted to, falling within the scope of the invention as claimed.

What is claimed as new is as follows:

55 A head levelling and holding device comprising: a yoke for mounting on the shoulders, said yoke including a pair of pivotally connected, spring-biased adjustable limbs for straddling the neck, said limbs terminating in upwardly curved free end portions, an upstanding, fixed 60 arm on the free end of one of the limbs, a pivotally adjustable, spring-biased arm on the free end of the other of said limbs, said arms for receiving and retaining the head in an upright position therebetween, a spirit level on the first named arm, and a pair of supporting legs depending from the limbs for resting on the chest.
